UNITED STATES PATENT OFFICE.

WILLIAM V. WALLACE, OF PITTSFIELD, MASSACHUSETTS.

AIR-MOISTENING APPARATUS.

SPECIFICATION forming part of Letters Patent No. 443,155, dated December 23, 1890.

Application filed January 24, 1890. Serial No. 338,018. (No model.)

To all whom it may concern:

Be it known that I, WILLIAM V. WALLACE, of Pittsfield, in the county of Berkshire and State of Massachusetts, have invented certain new and useful Improvements in Air-Moistening Apparatus, of which the following is a specification.

This invention has for its object to provide simple, durable, and effective means for moistening air by discharge of fine spray or mist from a water-supply pipe or system of pipes.

The invention consists, chiefly, in an improved spray-forming device consisting of a rotary valve fitted in a seat or casing, which is provided with an opening for the escape of a stream of water, said valve or its casing, preferably the former, having a groove or grooves, preferably of varying depth, adapted to permit the passage of a stream or streams of water at a tangent to the periphery of the valve through the said opening, when the said groove is adjusted so that a portion of it is in said opening, the latter being arranged to permit the unobstructed passage of said stream or streams through it. When the groove is of varying size, the size of the stream depends on the position of the valve, the varying size of the groove enabling it to supply a very fine stream or coarser stream, as may be desired.

A deflecting-plate is arranged in position to break up the stream of water discharged from the valve and convert the same into spray. A trough or receptacle is provided under the valve and deflecting-plate to receive the water that drips from the deflecting-plate and any water that may leak from the valve. The arrangement of the groove enables it to be freed from sediment by partly rotating the valve in its casing, said movement wiping off the valve, so to speak, or, in other words, loosening any deposits of sediment or foreign matter that may have accumulated in the groove, so that such deposits will be readily removed by the escaping water. When a number of the improved valves are arranged in one apartment as an air-moistening system, means are provided for the simultaneous rotation of all the valves to give the described wiping or sediment removing action, all of which I will now proceed to describe and claim.

Of the accompanying drawings, forming a part of this specification, Figure 1 represents a perspective view of a valve and its casing embodying my invention, said figure showing 55 also the deflecting-plate and drip-receptacle and means for rocking or rotating the valve to cause the described wiping action. Figs. 2 and 3 represent perspective views of the valve removed from the casing, the former 60 showing one groove and the latter a series of grooves in the periphery of the valve. Fig. 4 represents a transverse section of the valve and its casing on an enlarged scale. Fig. 5 represents a longitudinal section of the valve. 65 Fig. 6 represents a transverse section of the valve and casing, showing an auxiliary valve-wiping device. Fig. 7 represents a transverse section of the valve and its casing, showing a shield or guard arranged over the valve to 70 prevent the admission of lint and other foreign matter. Fig. 7^a represents a transverse section of the valve and its casing, showing the groove made in the casing. Fig. 8 represents a perspective view of a series of my improved valves and means for simultaneously 75 rotating the same.

The same letters and figures of reference indicate the same parts in the drawings.

In carrying out my invention I provide a 80 valve-casing *a*, having an internal seat or socket formed to receive a cylindrical valve *b*, which is adapted to rotate in the casing, said valve and its seat being preferably of tapering form, as shown in Figs. 2, 3, and 5, 85 so that the valve can be adjusted endwise to compensate for wear.

In the construction shown in Figs. 2, 4, 6, and 7 the valve is provided with a tapering groove *c*, which at one end is extremely fine, 90 and is gradually deepened from said end until it reaches a cavity *d*, formed in the periphery of the valve. The casing is provided at one side of the valve with an opening *g*, which exposes a portion of the valve, and is 95 arranged so that the valve may be turned to bring any desired part of the groove *c* into said opening. The casing is formed to fit closely on the periphery of the valve in the vicinity of the cavity *d*, as shown in Fig. 4. 100 When the valve is turned so that the cavity *d* is covered by the casing, there is no es-

- cape of water through the opening *g*. When the valve is turned so that the cavity *d* communicates with the water-supply and a part of groove *c* extends into opening *g* of the 5 casing, a stream of water is discharged through said groove and through the said opening *g* against the deflecting-plate *j'*, the size of said stream being dependent upon the adjustment of the valve. If the valve be 10 turned so that only the smallest end of the groove *c* extends into the opening *g*, the stream of water will be extremely minute; but if the valve be turned so that a larger portion of the groove enters said opening the 15 stream will be correspondingly larger. The impingement of the stream thus discharged against the deflector *j* causes the stream to be broken up into fine mist and distributed through the surrounding air. The water 20 that accumulates on the deflector drops into a reservoir *k*, which is attached by any suitable means to the water-supply pipe *i*, and is located under the valve and deflecting-plate. The receptacle *k* is preferably provided with 25 a waste-pipe *l* to permit the escape of the water that falls into it.
- It will be seen from the foregoing that a stream of water of any desired size can be produced, so that the degree of moisture furnished may be varied as circumstances may 30 require. It will also be seen that by partially rotating the valve after it has been standing for some time in a given position, any deposits of sediment that may have formed in 35 the groove *c* will be wiped off by the movement of the valve in contact with the casing or either of said parts, so that the groove will be cleared and the free passage of water through it be permitted. This adaptability 40 of the valve to be cleaned by the described wiping action is very important, because the fine groove *c* is very liable to become obstructed by impurities in the water, so that without provision for clearing the groove the device would soon become inoperative. I found 45 that by giving the valve a partial rotation first in one direction and then in the opposite direction the groove will be cleared of all obstructions. It is preferable to first rotate the 50 valve in the direction indicated by the arrow in Fig. 6, thus causing the water-delivering portions of the grooves to pass under the casings (or under the wiper *r*, hereinafter referred to) at the left-hand side of the opening *g* and viewed in Fig. 6, the casing (or wiper) being thus caused to force the obstructions from the delivering ends of the 55 grooves, after which the valve is turned back to its operative position.
- 60 To permit the described rotation of the valve I provide the latter with an arm *m*, which may be moved by any suitable means—such, for example, as a wire rope *o*, having attached to it enlargements *r r*, located at 65 opposite sides of the arm *m*, so that by movement of the rope *o* in one direction one of said enlargements will strike the arm *m*

and turn the valve in one direction, while an opposite movement of the rope *o* will cause the other enlargement to strike said arm and move the valve in the opposite direction. In Fig. 8 I have shown a series of these improved valves with a single rope *o* engaged in the manner described with the arms *m* of all the valves, said rope passing around pulleys *p* 75 and being connected with the sprocket-chain *q*, which is engaged with a sprocket-wheel *r'*, supported by a shaft journaled in suitable bearings and provided with a hand-lever *s*, whereby the wheel *r'* may be turned in either 80 direction and caused to move the rope so as to rotate and wipe all the valves simultaneously.

In Fig. 6 I have shown a rubbing or wiping device composed of a spring arm *u*, attached 85 to a suitably-fixed support and having at its free end a rubber piece or pad *v*, which bears upon the periphery of the valve *b* at a point between the sides of the opening *g*, said opening being made wider in this case than 90 in the forms shown in Figs. 1 and 4. The wiping device *u* serves as an auxiliary to the casing in wiping or clearing out the groove *c*. I do not limit myself, however, to the use of 95 this auxiliary wiper, as in most cases the contact of the valve with the casing is sufficient to effect the desired wiping or clearing out action.

In Fig. 7 I have shown a sheet-metal shield *w* attached by set-screw *x* to the casing *a* and 100 arranged over the opening *g* so that it will prevent the particles of lint that may be floating in the air from falling into said opening and obstructing the groove. The deflector *j* is here shown as connected by a pivot *y* with 105 an arm *z*, suitably attached to the valve-casing *a*. Said deflector may be supported in any other suitable way. I prefer to make the valve *b* hollow, as shown in Fig. 5, and provide its periphery with an orifice *3* to permit water to 110 pass from the periphery of the valve into its interior, such water escaping through an orifice *4*, formed in one end of the valve, as shown in Fig. 5. Said orifice *3* is located near the delivering end of the groove *c*, so that when the 115 valve is adjusted so that a stream is escaping through the groove *c* the water that may accumulate on the valve within the opening *g* will fall through the orifice *3* without obstructing the stream. If the valve had no opening 120 *3*, the accumulating water would prevent the escape of a very fine stream through the opening *g*.

I do not limit myself to the details of construction here shown, but may vary the same 125 in many ways without departing from the spirit of the invention.

The water-supply pipe *i* may be suspended by suitable hangers from the ceiling of the room, and the waste-pipe may be connected 130 by clamps *C* with the supply-pipe *i*. The waste-pipe should have a sufficient pitch or inclination to enable it to carry off the waste water, and for convenience I give the supply-

pipe the same pitch, so that the two may be parallel.

I do not limit myself to making the groove *o* of varying depth, as the described wiping action caused by rocking the valve in the casting would be effectual in removing sediment from the groove if the latter were of uniform depth.

Fig. 3 shows a modification in which the valve is provided with several peripheral grooves, and said grooves are shown as being of uniform depth, said grooves being of different lengths, so that when the valve is in one position water will flow from a less number of grooves than when the valve is in another position.

It is obvious that the valve may have one groove of uniform depth instead of a series, and if desired the valve may have a series of grooves of varying depth. I prefer the varying-depth groove, because I am enabled by the variation to regulate the size of the stream discharged, as above stated. If desired, the groove or grooves may be made in the casing instead of in the periphery of the valve.

Fig. 7^a shows a groove *c'* made in the casting, said groove being wiped by the rotation or rocking of the valve and shut off from the water-supply by turning the valve so that the cavity *g* is covered by the portion *5* of the casing, the lower end of the groove terminating above said portion.

I claim—

- 35 1. In an air-moistening apparatus, the combination, with a valve-case provided with inlet and outlet ports, of a turning-plug fitted therein and provided with a groove partially surrounding its circumference in the plane of the ports and of length sufficient to establish communication between the ports, and a deflector-plate secured in front of the outlet-port in the path of the outflowing stream, substantially as and for the purpose set forth.
- 40 2. In an air-moistening apparatus, the combination, with a valve-case provided with in-

let and outlet ports, of a turning-plug fitted therein and provided with a groove partially surrounding its circumference in the plane of the ports and tapering from the inlet toward the outlet port and of length sufficient to establish communication between the ports, and a deflector-plate secured in front of the outlet-port in the path of the outflowing stream, substantially as and for the purpose set forth.

3. In an air-moistening apparatus, the combination of a valve-casing communicating with a water-supply pipe and provided with a side opening *g*, a rotary valve in said casing, having a peripheral groove arranged to coincide with said opening and discharge a stream of water therethrough, and a wiper *v* in yielding contact with the periphery of the valve, as set forth.

4. In an air-moistening apparatus, the combination, with a valve-case having an outlet-port and an inlet-port, of a revoluble valve fitting said case and provided with a groove in its periphery adapted to be brought into communication with said ports or moved across the outlet-port by revolution of the valve, and a deflector arranged to be in line with a jet of water flowing from said groove, as and for the purposes described.

5. In an air-moistening apparatus, the combination, with a valve-case having an outlet-port and an inlet-port, of a revoluble valve provided with a groove in its periphery adapted to be brought into communication with said ports, said valve having an internal chamber and a port communicating therewith located adjacent to the outlet end of said groove, as and for the purposes described.

In testimony whereof I have signed my name to this specification, in the presence of two subscribing witnesses, this 18th day of November, A. D. 1889.

WILLIAM V. WALLACE.
